[57] ABSTRACT

8,13 : 13,20-Diepoxy-15,16-dinorlabdane is disclosed
as being a useful ingredient in flavouring compositions
for the aromatization of tobacco products.

2 Claims, No Drawings

FLAVORED TOBACCO COMPOSITION

DESCRIPTION OF THE INVENTION

This invention relates to a flavouring composition for the aromatization of tobacco or tobacco-substitute products, comprising as one of its ingredients a compound having the formula

The said compound is defined as 8,13 : 13,20-diepoxy-15,16-dinorlabdane. This invention relates further to a process for improving, enhancing or modifying the organoleptic properties of tobacco and tobacco products, which comprises adding thereto a small but effective amount of the compound of formula (I).

The present invention also relates to a tobacco or tobacco-substitute article comprising as flavour-modifying ingredient a small but effective amount of the compound of formula (I).

BACKGROUND OF THE INVENTION

It is well known that the tobacco used, for example, for the manufacture of cigarettes comprises a mixture of different types, to give the characteristic flavour and aroma desired in the smoke produced. Thus, cigarettes currently manufactured usually contain mixtures of Virginia, Maryland or Kentucky tobacco in combination with oriental or Turkish tobacco.

The respective proportions of the various types of tobacco are varied in order to obtain the particular flavour and aroma desired. It is also common practice to employ flavouring substances and humectants as additives to these tobacco mixtures to further enhance the organoleptic properties thereof.

We have now surprisingly found that the flavour and taste of tobacco products could be particularly enhanced and improved by the addition thereto of small amounts of the compound of formula (I).

PREFERRED EMBODIMENTS OF THE INVENTION

The compound of formula (I) can be used on its own, or in compositions comprising one or more other flavouring or odoriferous ingredients. The compound and compositions of the invention may be used in a variety of forms, depending upon their chemical nature, solubility and stability, but they are preferably used in solution. For the flavouring of tobacco, they are preferably added after ageing, curing and shredding, but before the tobacco is formed into cigarettes or other finished products. A convenient method for flavouring tobacco consists in spraying it with a solution of the flavouring compound or composition in alcohol, or in a mixture of alcohol and propylene glycol.

The compound of formula (I), whenever used in accordance with the invention, can develop a distinct woody, amber-like character. These properties are particularly developed on smoking the tobacco.

The proportion in which the flavouring agent of the invention is used in flavouring compositions or is added to tobacco can vary widely, depending upon the specific organoleptic effect it is desired to achieve and the type of tobacco to which it is added. Interesting flavour effects can be achieved with amounts ranging from 0.01 to 10 parts per million (ppm), preferably from 0.1 to 5 ppm and most preferably from 0.5 to 2 ppm, based on the weight of the product flavoured. Similarly, when used as a flavouring ingredient in a flavour composition, the proportion of compound (I) can vary within a wide range and being comprised between about 10 and 20%, based on the weight of the flavouring composition.

In all cases, the ranges mentioned can be varied, in order to achieve specific flavouring effects.

The compound of formula (I) is a polycyclic ketal whose structure was first determined by Ruzicka and Jeger — see namely Swiss Pat. No. 338,469 and Helv.-Chim.Acta, 37,543 (1954). Its olfactory properties were mentioned in the above said references and its utility in the perfumery was recognized ever since then. So far, however, no mention nor suggestion have been put forth concerning its possible usefulness in the field of flavouring.

Compound (I) can be prepared in accordance with known synthetic procedures — viz. described in the above cited Swiss patent — and in its pure form it occurs as a crystalline solid having a melting point at about 117°C.

Due to the simultaneous presence of several chirality centres in its molecule, compound (I) comprises several racemic or optical active stereoisomers. It has to be understood, however, that for all practical purposes isomeric mixtures, such as those directly obtained by the known cited syntheses, are preferably used.

The invention is better illustrated by, but not limited to the following Example.

EXAMPLE

100 g of "American blend" tobacco were sprayed with 1 g of a 0.001% solution of 8,13 : 13,20-diepoxy-15,16-dinorlabdane in 95% ethanol, and the tobacco thus flavoured was used to manufacture test cigarettes. As a control, cigarettes were also manufactured from the same tobacco sprayed with 95% ethanol alone. The smoke from the cigarettes was subjected to organoleptic evaluation by a panel of flavour experts, who unanimously stated that the smoke of the flavoured cigarettes possessed a typical and pleasant woody and amber-like flavour character.

What I claim is:

1. A process for improving, enhancing or modifying the organoleptic properties of tobacco and tobacco products, which comprises adding thereto a small but effective amount of a compound having the formula

2. A tobacco or tobacco-substitute article having added thereto a small but effective amount of a compound having the formula

said compound being effective to enhance the organoleptic properties of the article.

UNITED STATES PATENT AND TRADEMARK OFFICE
CERTIFICATE OF CORRECTION

PATENT NO. : 3,915,175
DATED : October 28, 1975
INVENTOR(S) : Paul Dietrich

It is certified that error appears in the above-identified patent and that said Letters Patent are hereby corrected as shown below:

Column 2, line 44, "0.001" should read --0.01--.
